UNITED STATES PATENT OFFICE.

AARON BURDWISE, OF BALTIMORE, MARYLAND, ASSIGNOR TO MUSICAL MANUFACTURERS' CORPORATION, OF BALTIMORE, MARYLAND, A CORPORATION OF MARYLAND.

FASTENING CONNECTER FOR STRINGS OF MUSICAL INSTRUMENTS.

Application filed January 18, 1926. Serial No. 82,150.

This invention relates to musical instruments, and especially to an improved fastening connecter for strings of musical instruments.

5 Although the invention is applicable to different kinds of string-instruments, it is especially useful and desirable in connection with violins; so the description of its application, use and operation will be 10 directed exclusively to violins and to that class of violin strings that are relatively or comparatively pliable and elastic, viz, gut strings or the like.

When a gut string breaks on a violin 15 while a violinist is playing or preparing to play therewith before an audience, it is very desirable and important to replace the string very quickly, lest the audience becomes impatient and displeased. Every one who has 20 experienced the difficulties in fastening a pliable and elastic string to a violin-key knows that such difficulties result mainly from the fact that the ordinary hole through the violin-key is very difficult of 25 access because it is located in the relatively small cavity of the violin-head; and another difficulty resides in the fact that new violin-strings are considerably curved in consequence of being sold and stored or 30 kept in coils of relatively small diameter; and a third difficulty resides in the fact of the string being relatively springy or elastic so it will not retain a permanent set after being bent, so it is incapable of being formed 35 into a locking bend such as is formed in the wire connecter which is relatively non-elastic and is capable of retaining such permanent set.

Therefore, one object of this invention is 40 to provide an improved and exceedingly simple connecter secured on the front end of a violin string, or comprising means to secure to the string, and being of comparatively stiff but non-elastic or slightly elastic 45 wire capable of retaining a permanent set and thereby automatically anchoring the string to the violin-key in consequence of the ordinary turning of the key for tensioning the string.

50 Another object is to provide an improved connecter of the character described but having the addition of lateral protrusions which may be in the form of convolutions of the wire, or may be of any appropriate form,

for indenting the violin-key's surface and 55 providing additional anchorages or anti-slipping elements.

Other objects and important features are pointed out or implied in the following details of description, in connection with the 60 accompanying drawings in which:

Fig. 1 is a longitudinal vertical sectional view through the front part of a violin-head and through a string-receiving hole of a violin-key, and a side view of a fastening 65 connecter attached to a violin-string and inserted through the said hole and slightly bent by rotation of the key.

Fig. 2 is a view of a part of the construction and combination shown in Fig. 1, but 70 the key being in a turned position to show how the fastening connecter is formed with locking bends, by rotation of the key, to prevent slipping of the wire or string when wound on the periphery of the key. 75

Figs. 3 and 4 are side views showing modified forms of the connecter and their respective means for securing the violin-string thereto.

Referring to these drawings in detail, in 80 which similar reference characters correspond to similar parts throughout the several views, and in which the violin-head H and violin-key K are of ordinary construction: The string S is of the relatively pliable and 85 springy or elastic kind such as gut or the like, and the fastening connecter C, C² and C⁴ (according to form of invention) is of comparatively stiff and bendable and non-elastic or slightly elastic wire of a diameter 90 approximately half that of the A violin-string, or smaller, according to the degree of malleability or flexibility.

While it is contemplated to secure the connecter to the violin-string by any appropriate means, I show several ways or means of fastening these parts, for instance, in Fig. 1, I show a loop lp in the wire, and a knot kn in the string S; in Fig. 3 the wire is formed with a loop lp³, and the string is formed 100 with a U-bend ub which may be retained in its shape, after engagement with the loop lp³ by a simple tie or band therearound or by a grasp of the thumb and finger of the user; and in Fig. 4 wire is inserted 105 through a hole or slot h in the string S, and one part of the wire extends parallel with the string and beyond the front end

thereof at c^4 while the other part of the wire is formed into helical convolutions cc^4 which hold the straight and parallel part of the wire in position on the string. These helical convolutions constitute lateral protrusions that slightly but effectively depress or indent the surface of the key for assisting the bends b^1 and b^2 in preventing the string from slipping on the key. The straight and helical parts in Fig. 3 are shown respectively at c^3 and cc^3 .

In applying the invention, the wire connector is first attached to the violin-string by any appropriate means (including the means herein described), and the substantially straight connector is then inserted in the hole of the violin-key and held against the front wall of the cavity of the violin-head while the key K is turned in the ordinary way for tensioning the string, thereby pressing the free end of the connector against the relatively close bottom of said cavity, thus making a sharp bend b^1 in the wire at the lower end of the hole through which it extends. The operator begins to pull back against the string as the winding proceeds, so a second sharp bend is made at b^2 . These bends form secure anchorages to increase the frictional and indented engagement with the surface of the violin-key. In fact, they are sufficient without the indented engagement of the lateral protrusions in cases where the strings or combined wire and string are long enough to form several turns around the violin-key.

It should be clearly understood that this

connector is not for the purpose of leading the string into the hole of the violin-key, but for avoiding the necessity of losing time and patience by attempting to insert the string in said hole. The wire, being relatively stiff and straight, is easily and quickly insertable in the hole, and being bendable and comparatively non-elastic, it is quickly and automatically converted into an anchor which secures the string to the violin-key so the latter can draw the string onto and around its periphery.

Although I have shown several forms of the invention, I have no intention to limit my patent protection to these forms, but the inventive idea embraces numerous other forms which lie within the scope of the combination claimed, as follows:

A musical instrument string comprising a main portion of gut or the like, and a key-connecting portion of comparatively stiff but bendable and comparatively non-elastic metal wire wound around and tightly embracing the front end of said main portion and extending forward beyond said front end and being of a size and shape which enables it to be inserted through the usual hole that extends laterally through a violin-key or the like, said wire thus being bendable by rotation of a violin-key or the like and thereby lockable to the latter for drawing the front end of said main portion onto and around the violin-key or the like.

In testimony whereof I affix my signature.

AARON BURDWISE.
